United States Patent Office

Des. 226,993
Patented May 22, 1973

226,993

HANDBAG

Arthur J. Fox, Edgewater Drive, Rte. 2, Box 234B,
Edgewater, Md. 21037

Filed Oct. 13, 1971, Ser. No. 189,075

Term of patent 14 years

Int. Cl. D3—01
U.S. Cl. D87—3 F

FIG. 1

FIG. 2

FIG. 3

FIG. 1 is a perspective view of a handbag showing my new design, the side opposite being a mirror image thereof, the portion of the handle not shown being plain and continuous;

FIG. 2 is a top plan view thereof; and

FIG. 3 is a bottom plan view thereof.

I claim:

The ornamental design for a handbag, as shown and described.
